Primary Examiner — Anhdao Doan*(74) Attorney, Agent, or Firm* — McCoy Russell LLP(57) **CLAIM**

The ornamental design for an integration management system for patient table, as shown and described.

DESCRIPTION

FIG. 1 is a front perspective view of a design for an integration management system for patient table including an upper table compartment and a lower table compartment according to the present invention.

FIG. 2 is a back perspective view of the integration management system for patient table of FIG. 1.

FIG. 3 is a top view of the integration management system for patient table of FIG. 1.

FIG. 4 is a right side view of the integration management system for patient table of FIG. 1.

FIG. 5 is a left side view of the integration management system for patient table of FIG. 1.

FIG. 6 is a back view of the integration management system for patient table of FIG. 1.

FIG. 7 is a front view of the integration management system for patient table of FIG. 1; and,

FIG. 8 is bottom view of the integration management system for patient table of FIG. 1.

The broken lines illustrate portions of the integration management system for patient table that form no part of the claimed design. The integration management system for patient table is shown with a symbolic break in its length. The appearance of any portion of the article between the break lines forms no part of the claimed design.

1 Claim, 5 Drawing Sheets(56)
